CARPET SECURING STRIPS

Merle R. Miller, Barrington, Ill.
(5314 W. Irving Park Road, Chicago, Ill.)

Filed Mar. 24, 1958, Ser. No. 723,512

4 Claims. (Cl. 16—16)

The present invention relates to carpet securing strips, and is particularly concerned with carpet securing strips of the type adapted to be secured to the floor adjacent the walls of the room for the purpose of engaging and securing the carpet, which extends over the strip to the wall at the baseboard or the quarter-round in case the quarter round is not removed and replaced over the carpet.

The present carpet securing strip is of the type often called "tackless," for the reason that it is not necessary to drive tacks through the carpet from the top to secure the carpet, since prongs, which may be in the nature of tacks, have their sharp ends extending upwardly from the strip, engaging the fabric of the carpet without projecting through the pile; and the present strips are preferably of the "pre-nailed" type, in which the strips are already provided with the nails extending through the strip at regularly spaced points and used for securing the strip to the floor.

When the floor is concrete, holes are preferably drilled and filled with wooden dowels in position to receive the ends of the nails; and when the floor is of wood, the nails are driven directly into the wood.

One of the disadvantages of the "tackless" carpet strips of the prior art now on the market lies in the fact that carpets are of different thickness, and those who install the strips are not always informed of the thickness of the carpet; and the strips of the prior art do not permit of adjustment after installation of the stripping, for different thicknesses of carpet.

Also, the carpets secured according to the prior art are not always sufficiently secured; and whenever furniture located away from the wall is moved toward the wall, it tends to drag the carpet with it toward the wall, sometimes unhooking the carpet which has been installed according to the prior art.

One of the objects of the invention is the provision of an improved carpet securing strip of the class described which permits the adjustment of the strip on the floor by sliding relative to the nails with which it is secured.

Another object of the invention is the provision of an improved "tackless" carpet securing strip of the pre-nailed type which carries the nails that are to secure it to the floor, the nails being so located on the strip that the strip may be driven closer to the wall to clamp the downwardly turned edge against the baseboard or quarter-round or other part of the wall, no matter how thick the carpet is and so that the carpet may be tightened at any time and fastened more securely than in the devices of the prior art.

Another object of the invention is the provision of a plurality of practical forms of pre-nailed carpet securing strip, all of which are slidably adjusted on the nails after they are driven into the floor, and all of which are adapted to hold the carpet in the position in which it is finally secured by driving the improved securing strip toward the wall to clamp the extreme end of the carpet

2

against the wall and secure the carpet more tightly on the prongs of the strip.

Another object of the invention is the provision of improved pre-nailed tackless carpet strips which are simple in construction, which include a minimum number of parts, which may be manufactured economically, and which provide for better securement of the carpet against the wall, baseboard, or quarter-round than in the devices of the prior art.

Another object of the invention is the provision of an improved pre-nailed, tackless carpet strip which is equally adaptable for use on wooden floors and concrete floors, and which may also be used for securing carpet which is installed on stairs or in halls, either in the form of a runner or from wall to wall, and which holds the carpet more securely and gives a more snug appearance.

Other objects and advantages of the invention will be apparent from the following description and the accompanying drawings, in which similar characters of reference indicate similar parts throughout the several views.

Referring to the two sheets of drawings accompanying this specification:

Fig. 1 is a fragmentary view in perspective of a wall-to-wall carpet installation, utilizing my improved carpet securing strips;

Fig. 2 is a fragmentary vertical sectional view taken through the floor, wall, and carpet assembly, embodying my invention, with the carpet in the position which it assumes when the tightening is completed;

Fig. 3 is a view similar to Fig. 2, with the strip and carpet secured on the strip, but before the final tightening and securing of the carpet;

Fig. 4 is a fragmentary view in perspective of one end of a carpet securing strip of the type shown in Figs. 2 and 3;

Fig. 5 is a view similar to Fig. 4 of a modification;

Fig. 6 is a fragmentary top plan view with the heads of the nails omitted, taken on the plane which is coincident with the top of the strip in Figs. 4 or 5;

Fig. 7 is a fragmentary vertical sectional view taken on the plane of the line 7—7 of Fig. 5, looking in the direction of the arrows;

Fig. 8 is a fragmentary sectional top plan view of a modified form of pre-nailed strip taken on a plane coincident with the top of the strip, looking downward, and omitting the heads of the nails;

Fig. 9 is a fragmentary top plan view of another modification in which a metal insert is corrugated to provide a plurality of nail gripping portions.

Fig. 10 is a fragmentary sectional view taken on the plane of the line 10—10 of Fig. 5, looking in the direction of the arrows;

Fig. 11 is a view in perspective of the nail retainer of the pre-nailed strip of Fig. 8.

Referring to Figs. 1—4, Fig. 1 shows a corner of a room with the two walls 20, 21 provided with baseboards 22, 23 and quarter-round 24, 25. The carpet stripping may be of any desired length, but is usually supplied in four foot lengths and may be cut off when required to fit inside the walls of the room.

Under ideal conditions the carpet is installed before the quarter-round is applied or the carpet may be installed after removing the quarter-round so that in such cases the quarter-round may be applied to the baseboard after the carpet has been provided in such size that it extends up against the baseboard; and the strips are located under ideal conditions close to the baseboard so that the quarter-round is located above the strips and prongs.

In many cases the quarter-round is not removed because it would be broken and split and would have to be wholly replaced; and in many cases the carpet is installed

against the side of the quarter-round, as shown in Fig. 2, in which case the quarter-round is of no assistance in holding the carpet on the prongs; and the curvature of the quarter-round makes it more difficult to secure the carpet tightly against it.

The present securing strips are adapted to be used both when the quarter-round is not removed and when the quarter-round is removed; and the present strips are very advantageous under the most adverse conditions when the quarter-round is not removed and replaced above the carpet.

The carpet securing strips are indicated at 26 and 27 in Fig. 1 nailed on the floor 28, which supports a floor pad 29, extending up to the carpet securing strips; and the entirety is covered by the carpet 30.

While the present securing strips are preferably made of plywood, they may also be made of strips of plastic of suitable thickness, width, and length.

Figs. 2-4 and 6 illustrate one preferred form of my carpet securing strip, which is shown in perspective in Fig. 4 and indicated by numeral 31. All the carpet securing strips described herein are preferably made of thin plywood, which may have three layers or plies, the upper layer 32 and the bottom layer 33 having the grain extending lengthwise, while the middle layer 34 extends crosswise of the length; and these layers are secured together under pressure and heat by waterproof glue or resin to form what is known as the "outdoor" type of plywood because it does not disintegrate by moisture. This is important because water may find its way through the carpet into the plywood, disintegrating it if it were not of the "outdoor" type.

The carpet securing strips may be of any desired width, such as, for example, one inch, and of any desired thickness, such as, for example, one-fourth of an inch, the thickness bearing a relation to the usual thickness of a pad 29, the edge 34 of which is brought up against the rear straight edge 35 of the carpet securing strip, in which this edge is formed at right angles to the top and bottom, the top being indicated at 36 and the bottom at 37.

The wall edge 38 of the carpet securing strip is preferably beveled upwardly, presenting a sharp upper edge 39, which is adapted to clamp or pinch the carpet against a quarter-round, even though the quarter-round curves toward the carpet securing strip below the edge 39.

The carpet securing strip 31 preferably has a multiplicity of diagonally extending prongs 40 located at regularly spaced points and arranged in two rows or series so that the prongs 41 in the outer row are staggered with respect to the prongs 40.

The prongs extend upward and are arranged to slant toward the edge 39, that is, toward the wall so that the fabric 42 of the carpet 43, bearing a pile 44, may have its fabric portion impaled on the prongs 40, 41; and the pull on the carpet, which is exerted by the carpet itself after tightening, tends to pull the carpet more tightly on the prongs.

These prongs may be in the nature of tacks of sufficient length and driven diagonally into the bottom of the carpet securing strip 31 so that their heads 44 are embedded in the bottom of the strip, forming a diagonal recess, leaving nothing to project from the bottom of the strip in so far as the heads of the tacks 40, 41 are concerned.

All of the different forms of strips described herein preferably include the structure which has been described so far.

The strip 31 is preferably of the pre-nailed type. The present carpet securing strips are preferably of the pre-nailed type; that is, they are sold with their nails secured in the strip; but they may also be sold with the nails detached.

Each length of strip is provided with a plurality of narrow saw slots 45, 46 located at regularly spaced points

and sufficiently narrow relative to the shanks of the nails 47 so that a nail may be driven into each slot 45, 46; and the nails will make a slight depression in the walls 48, 49 of each slot 45 sufficient to hold the nail 47 at the point where it is driven by friction.

The length of the tacks or prongs 40 is preferably such that the prongs project through the fabric 42 of the carpet 43; but they are located well below the top of the pile 44.

The length of the nails 47 is preferably such that the nails may extend through the strips 31 and into the floor 28 sufficiently to provide a firm anchorage for the strips 31.

The heads of the nails are indicated at 50; and they are 15 adapted to bear on the top 36 of the strips and may, if necessary, be embedded slightly in the strip 31, if that is necessary to hold the strips 31 in adjusted position.

The friction between the bottom of the head and the 20 top of the strip 31 and between the shank 47 of the nail and the walls of the slot 45 is sufficient to hold the strip in any adjusted position. The nails 47 are initially located at that end of each slot 45 which is closest to the beveled edge 38, as shown in Figs. 3 and 4, or when the strip is nailed to the floor, the nail is also located at 25 the left end of the strip in Fig. 4 so that the strip 31 may be spaced from the quarter-round 24 and the carpet may be installed and cut and turned down about the sharp edge 39, providing a carpet portion 51 which extends down between the quarter-round 24 and the beveled edge 38 to be clamped thereby.

After the carpet has been secured, strips located as 30 shown in Fig. 3, and tightened for a reasonable amount, the carpet may be further tightened by using a carpet tightener or other tool by driving against the edge 35 of the strip and forcing it toward the wall, the strip sliding on the nails 47 from the position of Fig. 3 to that of Fig. 2.

With such a structure the carpet may be fastened more securely, even against quarter-round; and the strips may be located without the wood stripper knowing the exact thickness of the carpet because the present strips may be adjusted after the carpet is hooked on the prongs and driven tightly against the wall.

Referring to Figs. 5 and 10, these are views of a modification of the carpet strip of Fig. 4, which are similar in every respect except that each of the securing nails 47 is provided with a washer 53 located on the nail between the head 50 and the carpet securing strip 31.

As available securing nails may have relatively small 50 heads, the washers 53 give an increased bearing surface on the top of the wooden strip and provide increased resistance in the way of friction for holding the carpet tight after the strip has been adjusted to the position of Fig. 2.

55 All of the other parts of the strip of Fig. 5 may be the same as previously described.

Referring to Fig. 8, this is a view similar to Fig. 6 of a modification in which the slots in the wooden strip 31 have been enlarged, but have been provided with metal 60 retaining members 54 for holding the nails in adjusted position in the strip, and for holding the strip in adjusted position relative to the nails.

The metal securing member 54 is shown in perspective in Fig. 11; and it may comprise a sheet steel or spring 65 bronze member which is of a size to fit in the enlarged slot 55, where it is held by the laterally projecting sharp prongs 56 and 57 driven into the wood from the top. These prongs are pointed and tapered on their lower edge, where they are also sharpened; and they are punched out 70 of the metal which forms the member 54.

This strip is formed with a cylindrical portion 58 at one end and a cylindrical portion 59 at the other end, these being of a size to receive and grip the shank of a nail 47 or 47a.

75 Between the nail recesses 57, 58 the body of the

member 54 curves inward at 60 on one side and curves inward at 61 on the other side, but it is open at 62. The thickness and resiliency of the metal strip is such that when the strip is secured by nails, the strip may be caused to slide on a nail in the position 47a (Fig. 8) until the strip is in the position of Fig. 2 and the nail is in the position indicated at 47 in Fig. 8.

The restriction at 60, 61 tends to hold the nail in its initial position at 47a and to resist movement of the strip from the position of Fig. 3 to that of Fig. 2; but the member 54 aids in holding the strip after adjustment in the position of Fig. 2.

Referring to Fig. 9, this is a view similar to Fig. 8 of another modification in which an enlarged slot 63 is provided with a sheet metal member 64, which may comprise a pair of similar members, each of which is provided with a prong 65 and a body having a plurality of corrugations 66, forming a plurality of places for holding the nail.

For example, there are four partially cylindrical recesses within which the shank 47 of a nail may be held. This permits the adjustment of the carpet securing strip to three additional positions by moving it from its first position, which would be equivalent to Fig. 3.

The metal members 54 and 64 are made of light resiliency metal and are preferably shorter than the thickness of the plywood strip; and the recess therein, which holds the nail, has a frictional grip on the shank of the nail so that the strip may be a pre-nailed strip.

The strips may also be used to secure runners or wall-to-wall carpet upon stairs. In securing the carpet on stairs, a short piece of the securing strip should be used at each of the lateral edges of the runner or solid carpet on the tread; and a similar short strip may be used on each riser.

The main securement of the carpet on the stair is by using a securing strip with downwardly directed prongs on the riser at the bottom, close to the corner formed by riser and tread, and another on the tread with prongs close to and directed toward the riser in the same corner. Thus the carpet will be drawn tightly into the corners of the stairway at the back of each tread and the bottom of each riser.

It will thus be observed that I have invented a plurality of different forms of carpet securing strips, all of which can be caused to engage the carpet more tightly, after the carpet is secured on the prongs, and all of which permit the clamping of the edge of the carpet tightly against the wall or quarter-round.

With the present securing strips the stripper need not know the exact thickness of the carpet; and the carpet is not likely to be pulled off the prongs by the moving of furniture toward the wall.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States is:

1. A pre-nailed carpet securing strip, comprising a narrow plywood strip of thickness substantially equivalent to the thickness of a carpet pad to be used with the strip, said strip having a multiplicity of diagonally extending upwardly projecting prongs turned toward the edge of the strip, which is to be adjacent a wall and adapted to be embedded in the fabric base of a carpet to secure the

carpet without projecting above the carpet, and a plurality of headed nails extending through said securing strip and frictionally held thereby, with their heads located uppermost on the same side as said prongs, for engaging the top of the securing strip, said securing strip having a transversely elongated parallel sided slot about each nail shank, said strip being backwardly and downwardly beveled at the edge toward which the prongs point, to provide a clamping edge for pinching a downwardly turned portion of the carpet to be clamped between the wall and the strip, the said parallel sided slots comprising saw cuts narrower than the diameter of the nail shanks for clamping the nail shanks in a strip preliminary to its use.

2. A pre-nailed carpet securing strip, comprising a narrow plywood strip of thickness substantially equivalent to the thickness of a carpet pad to be used with the strip, said strip having a multiplicity of diagonally extending upwardly projecting prongs turned toward the edge of the strip, which is to be adjacent a wall and adapted to be embedded in the fabric base of a carpet to secure the carpet without projecting above the carpet, and a plurality of headed nails extending through said securing strip and frictionally held thereby, with their heads located uppermost on the same side as said prongs, for engaging the top of the securing strip, said securing strip having a transversely elongated parallel sided slot about each nail shank, said strip being backwardly and downwardly beveled at the edge toward which the prongs point, to provide a clamping edge for pinching a downwardly turned portion of the carpet to be clamped between the wall and the strip, the said nails having their shanks located in that end of the slot which is adjacent the clamping edge of the clamping strip so that the carpet may be secured on the prongs and thereafter tightened by driving the strip toward the wall.

3. A pre-nailed carpet securing strip comprising a narrow plywood strip of substantially the same thickness as the carpet pad to be used with it, said strip having a multiplicity of upwardly extending diagonal prongs projecting from its upper surface and sloping toward an upwardly beveled clamping edge which is to be located toward a wall, said prongs comprising tacks driven diagonally upward through the strip from the bottom and projecting upwardly from the top of the strip sufficiently to engage and hold the fabric of an overlying carpet without projecting from the carpet, said strip having a plurality of transversely narrow parallel walled through slots for slidably supporting the strip on securing nails which are frictionally secured in said slots in position to be driven into the floor, the said through slots being saw cuts narrower than the diameter of the nail shank for gripping the nail shank in rounded portions of the slot formed by the driving of the nails.

4. A pre-nailed carpet securing strip according to claim 3, in which the securing nails are initially mounted in the slots at that end of the slot which is toward the beveled edge of the strip, thereby providing a maximum adjustment of the strips on the nails.
